US0D1036243S

(12) **United States Design Patent** (10) **Patent No.:** **US D1,036,243 S**
(45) **Date of Patent:** **** Jul. 23, 2024**

(54) **FLOOR UNDERLAYMENT**

(71) Applicant: **Progress Profiles S.p.A.**, Asolo (IT)

CA 1186470 5/1985
CA 181375 2/2019

(72) Inventor: **Dennis Bordin**, Asolo (IT)

(Continued)

(73) Assignee: **PROGRESS PROFILES S.P.A.**, Asolo (IT)

(**) Term: **15 Years**

(21) Appl. No.: **29/754,331**

(22) Filed: **Oct. 9, 2020**

(51) LOC (14) Cl. **08-05**

(52) U.S. Cl.

USPC **D8/380**

(58) **Field of Classification Search**

USPC D8/380; D25/138, 142, 144, 152, 153,
D25/156, 157, 158, 159, 160, 161, 163,
D25/199

CPC E04C 2/52; E04F 15/185

Primary Examiner — Keli L Hill

Assistant Examiner — Harold E Blackwell, II

(74) *Attorney, Agent, or Firm* — Sheridan Ross P.C.

(57) **CLAIM**

The ornamental design for a floor underlayment, as shown and described.

DESCRIPTION

FIG. 1 is a top perspective view of a floor underlayment showing my new design;

FIG. 2 is a bottom perspective view of the design depicted in FIG. 1;

FIG. 3 is a right elevation view of the design depicted in FIG. 1;

FIG. 4 is a left elevation view of the design depicted in FIG. 1;

FIG. 5 is a front elevation view of the design depicted in FIG. 1;

FIG. 6 is a back elevation view of the design depicted in FIG. 1;

FIG. 7 is a top plan view of the design depicted in FIG. 1; and,

FIG. 8 is a bottom plan view of the design depicted in FIG. 1.

The broken lines show portions of the floor underlayment which form no part of the claimed design.

1 Claim, 6 Drawing Sheets
